UNITED STATES PATENT OFFICE

127,797

DESIGN FOR A SUCTION NOZZLE

Lurelle Guild, Darien, Conn., assignor to Electro-lux Corporation, New York, N. Y., a corporation of Delaware

Application April 23, 1941, Serial No. 100,581

Term of patent 14 years

To all whom it may concern:

Be it known that I, Lurelle Guild, a citizen of the United States of America, residing in Darien, Connecticut, have invented a new, original, and ornamental Design for a Suction Nozzle, of which the following is a specification, reference being had to the accompanying drawing, forming a part thereof and of which

Fig. 1 is a front perspective view of my new design of a suction nozzle; and

Fig. 2 is a rear perspective view.

I claim:

The ornamental design for a suction nozzle, as shown.

LURELLE GUILD.
